UNITED STATES PATENT OFFICE.

LOUIS CLEMENCET, OF WEST HOBOKEN, NEW JERSEY, ASSIGNOR TO THE
ALEX. SMITH & SONS CARPET COMPANY, OF YONKERS, NEW YORK.

DESIGN FOR A CARPET.

SPECIFICATION forming part of Design No. 20,261, dated November 4, 1890.

Application filed October 10, 1890. Serial No. 367,646. Term of patent 3½ years.

To all whom it may concern:

Be it known that I, LOUIS CLEMENCET, a citizen of the United States, residing at West Hoboken, Hudson county, New Jersey, have 5 invented a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design consists of the body A and the border B. The body A is composed of groups of large conventionalized leaf and somewhat rose-shaped flower forms, the groups lying on 20 a shaded groundwork of leaves and connected

by stems or branches. The border B is composed of an inner ornamental margin, a middle portion of groups of leaf forms and conventionalized leaf and somewhat rose-shaped flower forms with stems, and an outer margin 25 containing small gem ornamentalations.

What I claim as new, and desire to secure by Letters Patent, is—

1. The design for carpets, consisting of the body A, substantially as shown. 30
2. The design for carpets, consisting of the border B, substantially as shown.
3. The design for carpets, consisting of the body A and the border B, substantially as shown.

LOUIS CLEMENCET.
